UNITED STATES PATENT OFFICE.

WILL M. SAWYER, OF CHICAGO, ILLINOIS, ASSIGNOR TO THE WHEELING CORRUGATING COMPANY, OF CHICAGO, ILLINOIS, A CORPORATION OF WEST VIRGINIA.

KNOCKDOWN METALLIC STRUCTURE.

1,054,317.

Specification of Letters Patent. Patented Feb. 25, 1913.

Application filed December 11, 1911. Serial No. 664,989.

To all whom it may concern:

Be it known that I, WILL M. SAWYER, a citizen of the United States, residing at Chicago, in the county of Cook and State of Illinois, have invented certain new and useful Improvements in Knockdown Metallic Structures, of which the following is a specification.

My invention refers in general to knock-down metallic structures, and particularly to the smaller buildings of that class that are especially appropriate for use throughout the farming districts for smokehouses, tool-sheds, and constructions of similar nature whose use is only required for a portion of the year.

I aim to produce a building that may be readily set up and taken down by unskilled laborers, and one which may be stored with but small chance of any of the parts being lost.

A further object of my invention is to produce a structure of the kind described which will be simple in construction, cheap to manufacture, and which will possess exceptional strength and durability.

Further aims and advantages will appear as my invention is better understood from the following description, which, taken in connection with the drawings illustrate one preferred embodiment thereof.

Referring to the drawings:—Figure 1 is a front elevation of a structure embodying my invention. Fig. 2 is a vertical section on the line 2—2 of Fig. 1. Fig. 3 is a vertical section on the line 3—3 of Fig. 2. Fig. 4 is a horizontal section on the line 4—4 of Fig. 1. Fig. 5 is an enlarged horizontal section on the line 5—5 of Fig. 1, showing details of the means of connecting two side walls together. Fig. 6 is an enlarged vertical section showing the means of locking the roof members, the stiffening member and the side wall together.

Referring to the drawings, the structure embodies the front wall 10, the rear wall 11, and the two side walls 12. These walls may be either made of a single sheet of metal or they may be formed of a plurality of vertically disposed sheet metal sections 13. The vertical edges of the front and rear walls 10 and 11 are bent outwardly to form the flange 14 substantially at right angles to the plane of the said walls. These vertical edges are then further rolled back upon

themselves to slightly less than one circumference, forming thereby on either side of the said walls, a vertical cylindrical roll 15. The two side walls have their edges bent inwardly to form the flanges 16 substantially at right angles to the plane of the said walls, the vertical edges of said walls being then rolled back upon themselves to form the cylindrical rolls 17. The inwardly disposed rolls 17 are thus adapted to slip over and embrace the outwardly disposed rolls 15 to connect the side walls 12 to the front and rear walls 10 and 11 by merely disposing the rolls 15 within the rolls 17.

The side walls 12 and the rear wall 11 are each provided with a horizontal flange 18 formed at the bottom of the structure by bending outwardly the lowermost edges of the said walls. The said flanges 18 have riveted beneath them thereto, the stiffening members 19, formed of strips of metal having one edge 20 bent to embrace the said flange and the other edge 21 bent to form a roll within the construction.

The front wall 10 is formed of two vertically disposed side members 22 which are connected together at the top by the sheet metal member 23 and at the bottom by the member 24, said members being riveted to the vertical sections 22. A door 25 is fastened to one member 22 by a plurality of hinges 26 and is adapted to be locked to the other member 22 by the latches 27. The member 23 is provided with a tongue 28 between the vertical sections 22. The said tongue is bent to form the inwardly disposed flange 29 and has its edges bent upwardly to form the lip 30 providing the channel 31 between the said lip and the said member 23. The upper edge of the member 23 is bent outwardly to form the flange 32 substantially in the plane of the roof and is provided with the lip 33 forming one side of a channel 34 above the channel 31. In the member 23 are provided the ventilating apertures 34 adapted to be closed by the slide 35 which is movable back and forth along the channels 34 and 31. The bottom member 24 is provided at its top with a tongue 36 which is bent to form the flange 37 within the construction and is folded back upon itself to form the downwardly disposed lip 38 which is spaced from the member 24 to form a channel 39. The said member 24 is provided at its base with the flange 40 which is 110

formed by bending outwardly the bottom portion thereof and folding it back upon itself. The edge 41 of the said bent back portion is disposed upwardly and spaced from the main portion of the member 24 to form the channel 42 below the channel 39. The member 24 is further provided with the aperture 43 for the reception of fuel which is adapted to be closed by the slide 44 moving in the channels 39 and 42. The bottom edges of the vertical sections 22 are bent outwardly to form the horizontal flanges 45. A stiffening member 46 is fastened to the bottom of said flanges 45 and to the flange 40 of the member 24, said stiffening member being composed of a metal sheet having one end 47 bent to embrace said outwardly disposed flanges 45 and 40 and the other edge bent to form a roll 48 within the construction. The vertical sections 22 have their adjacent edges 49 bent inwardly between the members 23 and 24 to form the vertical flanges 50, terminating in the turned back lips 51.

The rear wall 11 is provided with a stiffening member 52 formed of a strip of metal having one edge rolled back upon itself to form the roll 53 and the other edge 54 riveted to the said wall 11 by means of the rivets 55. The side walls 12 are provided with stiffening members 56 of similar construction formed of the rolled back portions 57 and having the flat edges thereof 58 riveted to the walls 12 by the rivets 59 adjacent to the top of said walls. The side walls 12 are provided with hanger supports 60, each hanger support being formed of a lateral member having one edge 61 riveted to the walls 12 and the other edge 62 bent to support a plurality of transverse hanging means 63, said means being composed of a sheet of metal rolled back upon itself to form a spiral roll, said spiral roll being flattened at its ends 64 to form hooks to engage the upturned edge 62 of the hanger support 60.

The upper edge of the walls 11 and 12 and the sections 22 of the wall 10 are bent outwardly to form the flanges 64, said flanges being substantially in the same plane. The stiffening members 65 are riveted to the flanges 64, said members having one edge 66 bent to embrace the flanges 64 and the other edge turned back upon itself to form the roll 67 within the construction, the innermost extremity of said roll being bent radially inward to form the flange 68.

Two roof members 69 are adapted to slide inwardly from the sides 12 and to this end, 60 are provided with the downwardly disposed flange 70 and the horizontal flange 71 formed by bending the ends 72 of the said members 69 and the sides 73 downwardly and back upon themselves to form the flange 65 70 and inwardly to form the horizontal

flange 71, said roof members embracing between the said flange 71 and the main portion thereof, the outwardly disposed flange 64 of the side walls and the stiffening member 65. The said sections 69 are bent back upon themselves about their adjacent ends to form the lips 74 and the locking member 75 formed of a sheet of metal having its edges turned under, as at 76, is provided and adapted to engage the turned back edges of the members 69 within the under turned edges 76 by sliding the member 75 from the front of the structure to the rear. The locking member 75 is bent downwardly at the front end thereof at 77 and returned upon itself, terminating in the rearwardly projecting lip 78 adapted to engage beneath the flange 32 and the stiffening member 65. The said interlocking member 75 is provided at its rearward extremity with the portion 79 which, when the said interlocking member is in position, may be bent downwardly and returned upon itself to form the lip 80 to engage the flange 64 and the stiffening means 65 to complete the construction.

It will be seen that the structure after it has left the factory may be assembled without the use of any bolts or rivets or, in fact, any auxiliary agencies whatever, it being only necessary to slide the rolls at the edges of the side walls one within the other, place these side walls in a vertical position, slide in from the two opposite sides the roof members and lock them in position by means of the locking member which in sliding into position binds the various parts into one homogeneous whole. It is only necessary to bend down the back portion of the said interlocking member to complete the assembling of the construction.

It is understood that various changes in the form, proportion and mechanical detail of the various parts may be resorted to without departing from the spirit and scope of the invention or sacrificing any of the material advantages thereof, the embodiment of the said invention, as disclosed in the foregoing description and the accompanying drawings, being merely one form thereof.

What I claim is:

1. A knockdown metallic structure, comprising side walls, roof members adapted to be slid toward the center from the sides, and means embracing and locking said sections together and to the construction, said means having its ends formed to embrace the tops of the side walls when the said ends are bent downwardly.

2. A knockdown metallic structure, having side walls, roof members adapted to be slid in toward the center from the sides, and means adapted to be slid from the front toward the back to lock the said sections together in position, said means being adapted

to engage the top of the side walls at the front when the said means are in position and having a projection thereon at the rear adapted when the end is bent down to interlock with the top of the rear wall when said means is in position.

3. A knockdown metallic structure, having side walls, roof members adapted to be slid in toward the sides, and means adapted 10 to be slid over the adjoining edges of said roof plates to lock the same together, said means having an end shaped to engage an edge of the said roof plates and an edge of the side wall and having the other end 15 folded back parallel to itself and adapted to engage the underside of the said roof plates when the end is bent downwardly after the members are in place.

4. A knockdown metallic structure, having side walls, roof sections adapted to be slid into position from the sides of the said structure, adjoining edges of the said roof sections being folded back upon themselves 20 to provide flanges, and a member having the 25 edges cut away adjacent the ends of the said member and turned back upon themselves to engage the said flanges upon the roof sections, one end of the said member being

adapted to embrace the top of a side wall and the edges of adjacent sections and the 30 other end of the said member being adapted to be folded down to embrace the opposite edge of the side wall and the edges of the said section.

5. A knockdown metallic structure, having 35 side walls, a flat supporting member embracing the top of said side walls and extending within the construction adapted to support and stiffen a roof plate, a roof plate disposed flatly upon the said supporting member and folded at its edge to embrace a portion of the said member without the construction.

6. A knockdown metallic structure, having 40 a side wall bent outwardly at its top to 45 form a flange, a roof plate bent to embrace the said flange, and means interposed between the said roof plate and the said flange, spacing apart an edge of the roof plate from the said flange to prevent the entrance of 50 water between the flange and roof plate through capillary action.

WILL M. SAWYER.
